GUIDE CAP

Gilbert Hudson, Glendale, Calif., assignor to Adapto, Inc., Las Vegas, Nev., a corporation of Nevada

Application November 14, 1955, Serial No. 546,582

2 Claims. (Cl. 128—272)

This invention relates to a dispensing stopper for vials and the like and, more particularly, to an improvement for such dispensing stoppers to assist in the withdrawal of solution from the vials with which such stoppers are used.

In a patent to Perelson, No. 2,667,986, there is described a dispensing stopper for use in combination with a vial containing a solution usually used for hypodermic injections. This stopper contains a hollow needle which is supported therein and communicates with the interior of the vial. The needle is covered over by a diaphragm. The diaphragm is made of rubber and may be impaled on the needle by pressing a syringe neck against the diaphragm. The diaphragm is pushed down below the point of the needle, whereby the syringe may be filled from the solution in the bottle through the needle. Care must be taken in using this arrangement, since if the syringe is not properly aligned with the needle in the stopper, both the end of the syringe as well as the needle may be damaged when the syringe is pressed down over the diaphragm. Also, after loading, the syringe may be withdrawn from the dispensing stopper angularly, thus bending the needle tip and causing difficulty upon subsequent attempted utilization of the arrangement.

In loading a syringe, the syringe must be held in position with the bottle against the push of the diaphragm. This requires holding syringe and bottle together with one hand while the other is used to fill the syringe. This is not easy.

An object of the present invention is the provision of a syringe guide and holding cap which will fit upon the dispensing stopper device described in the patent which guides a syringe to the filling needle and, also, holds it in place.

Another object of the present invention is the provision of a novel syringe guide and holding cap which may be used on any number of bottles for the purpose of guiding and protecting a syringe in the manner previously described.

Still a further object of the present invention is the provision of an inexpensive syringe guide and holding cap which prevents damage to a syringe when it is employed in the manner described above.

Yet another object of the present invention is the provision of a syringe guide and holding cap which enables the easy filling of a syringe.

These and other objects of the invention are achieved by a guide cap having a first part which is seated over the mouth of a vial which contains the type of dispensing stopper described above. The second part of the cap consists of the syringe guiding and holding structure. The first part consists of slotted walls defining an opening large enough to fit over the ferrule of a vial and terminating in a lip which fits under the ferrule, thus grasping the vial. The second part consists of slotted walls defining an opening just large enough to serve as a guide and to align the syringe over the dispensing needle. In addition,

2

an inward radial flange is provided at the top of these slotted walls which fits into a groove between the metal base and glass graduate portion of the syringe, thus locking it in place.

5 The novel features that are considered characteristic of this invention are set forth with particularity in the appended claims. The invention itself, both as to its organization and method of operation, as well as additional objects and advantages thereof, will best be understood 10 from the following description when read in connection with the accompanying drawings, in which:

Figure 1 shows a view of a vial of the type previously described and an embodiment of the invention positioned thereover;

15 Figure 2 is a cross-section of the embodiment of the invention in combination with a vial and dispensing stopper of the type described, also showing the base of a syringe in position over the diaphragm; and

Figure 3 is a cross-section of an embodiment of the invention in combination with a vial and dispensing stopper of the type described and also shows how the syringe is guided properly to the dispensing needle by the embodiment of the invention.

20 Referring now to Figure 1, there may be seen a vial 10 of the type usually employed to hold a solution which is to be used for injections. The mouth of the vial may be closed by a self-sealing dispensing device 12 of the type described in Patent No. 2,667,986 referred to previously, which is held in the vial by a metal ferrule 14. This 25 device has only a shallow boss 15 for indicating where a syringe is to be applied for filling. This does not prevent accidental angular application or angular withdrawal of the syringe, thus causing damage to both syringe and stopper with a possibility of such deformity to the needle as to render it useless. The embodiment of the invention comprising an aligning cap is positioned over the vial and is composed of two parts. A first part 16 is the member for grasping the neck of the bottle and fits over the metal ferrule 14. The second part is a syringe 30 guiding and holding portion 18 which is integrally united with the neck-grasping member 16 but for convenience of manufacture may be made separately and then fitted together. Both portions of the guide and holding cap have a circular slotted walls which define the openings for the 35 syringe base and for the vial top and yet enable the withdrawal of both when required. The slotted walls of both parts extend from a common base member 17 which has an opening therein of the same diameter as said syringe- 40 guiding part. An inwardly extending flange 19 on the outer end of the portion 18 fits into the groove which is found between the metal base and glass graduate portion of syringes.

45 Regarding now the cross-section of the invention shown in Figure 2, this invention is shown in position on the vial. The circular walls of the neck-grasping portion 16 are in intimate contact with the ferrule 14. They have a slight lip 20 at their ends whereby the guide cap grasps the neck of the vial and is not withdrawn when 50 the syringe is withdrawn. The circular walls are slotted for the purpose of enabling the guide cap to be forced over the top of the bottle, despite the lip, as well as for the purpose of enabling its being withdrawn therefrom without cracking or breaking. The syringe guide and 55 holding portion 18 also consists of slotted circular walls defining an opening large enough to accurately guide a syringe and to enable its ready removal. This opening, when the cap is in position, is over the boss 15. At the outer end of these walls is an inwardly extending flange 60 19 which fits into the groove found in all metal base syringes where they are joined to the glass graduate portion of the syringe. The slotted walls enable the syringe 65

base to be inserted or removed from the guide portion without cracking the cap.

The dispensing stopper, in conjunction with which this invention may be used, includes a base 22 and a hollow needle 24. The base has an opening therethrough 26 and also supports the hollow needle by one end in alignment with that opening. A resilient tubular member 28 is seated against the base 22 and also is formed integrally with a diaphragm 30, which serves to cover the other end of the needle. The resilient tubular member 28 completely encloses the needle. The diaphragm 30 is made of a rubber material which is of the self-sealing type. As shown in Figure 3, when the diaphragm is forced down over the needle by a syringe 32, the needle end is exposed and the syringe may be filled. The resilient member 20 is deformed and exerts an upper pressure, so that upon withdrawal of a syringe the diaphragm will be forced back over the needle and thus it self-seals the opening made therein by the needle and thus maintains the needle and the solution in the vial sterile.

Figure 3 also shows the invention being employed to guide a syringe 32. As may be seen there, the syringe is inserted into the guiding portion of the invention 18, which insures that it is brought properly and directly in alignment with the needle 24. Furthermore, the flange 19 enters the groove in the syringe base and, together with the walls of the guiding portion of the cap, holds the syringe firmly in place during the filling operation against the outward push of the diaphragm. Thus, the assembly may be held in one hand for filling with a minimum of difficulty. Upon filling the syringe with a desired quantity of fluid, if desired, the vial is re-inverted and the syringe may then be withdrawn without either deforming the end of the needle or widening or adversely affecting the base of the syringe. The slotted walls in the guiding and holding portion of the cap permit the syringe withdrawal. The syringe may then be fitted with the needle which is to be used for the actual injection.

It will be appreciated that the embodiment of the invention is not necessarily confined to being used with only a single bottle, but may be used wherever required. Furthermore, the holding and guiding cap may be used with any other suitable type of dispensing stopper or without one, if desired.

Accordingly, there has been shown and described a novel, useful, inexpensive and simple device for guiding, holding, and protecting syringes for filling from vials having a dispensing stopper.

I claim:

1. An aligning and holding cap for guiding a syringe to the covered needle in a self-sealing dispensing stopper of a vial, said cap comprising a first portion having circular slotted walls adapted to fit over the top of said vial, a lip at one end of said circular walls, a second portion connected to said first portion including circular slotted walls having an inwardly extending flange and defining an opening adapted to guide and maintain in position a syringe in operative relationship with said covered needle.

2. An aligning and holding cap for utilization with a vial having a self-sealing dispensing stopper and a covered needle for filling syringes comprising a base member, slotted circular walls extending from one side of said base member and defining an opening adapted to fit over the top of said vial, an inwardly extending lip at one end of said slotted circular walls adapted to grasp said vial, circular slotted walls extending from the other side of said base member having an inward radial flange at the outer end thereof and defining an opening adapted to receive, guide, and hold said syringe in operative relationship with said needle.
